UNITED STATES PATENT OFFICE.

SAMUEL E. GUINN, OF JOHNSON CITY, TENNESSEE, ASSIGNOR TO S. E. GUINN MANUFACTURING CO., OF CINCINNATI, OHIO, A CORPORATION OF NEW YORK.

DESIGN FOR AN INKSTAND.

Application filed November 12, 1924. Serial No. 11,353. Term of patent 14 years.

To all whom it may concern:

Be it known that I, SAMUEL E. GUINN, a citizen of the United States, residing at Johnson City, in the county of Washington and State of Tennessee, have invented a new, original, and ornamental Design for an Inkstand, of which the following is a specification, reference being had to the accompanying drawing, forming part thereof, and in which—

Fig. 1 is a perspective view of the ink stand.

Fig. 2 is a side elevation of the same.

I claim:—

The ornamental design for an inkstand, as shown.

SAMUEL E. GUINN.
